UNITED STATES PATENT OFFICE.

MARION C. HARRISON, OF KANSAS CITY, MISSOURI.

CUT-OFF FOR DOWN-SPOUTS.

SPECIFICATION forming part of Letters Patent No. 693,009, dated February 11, 1902.

Application filed March 22, 1901. Serial No. 52,349. (No model.)

To all whom it may concern:

Be it known that I, MARION C. HARRISON, a citizen of the United States, and a resident of Kansas City, in the county of Jackson and State of Missouri, have invented new and useful Improvements in Cut-Offs for Down-Spouts, of which the following is a specification.

My invention relates to down-spout cut-offs, and in practice is attached to the lower end of a down-spout or water-conductor which conducts the water from the eaves-trough of a building to the ground and is so arranged when in position that the water which passes through it can be shifted from the pipes leading to a cistern to waste-pipes leading to an ordinary sink or main of a sewer or can be shifted from the waste-pipe to the pipe that leads to the cistern.

In further describing my invention I will do so by referring to the drawings, in which—

Figure 1 is a vertical section. Fig. 2 is a plan view of my invention, taken on line Y Y of Fig. 1, with the parts above said line being removed. Fig. 3 is a sectional view taken on line Z Z of Fig. 1, showing the position of a shifting-rod pivotally secured to said cylinder at 12, which is adapted to shift a revolute cylinder for shifting the downpour of the water from one exit to the other. Fig. 4 is a vertical portion of one of the sides of my invention, taken also on line Z Z of Fig. 1, showing a slot therein through which the shifting-rod, Fig. 5, is adjustably manipulated for the reversible movement of a revolving cylinder. Fig. 6 is a broken section of the shifting-rod in relative position to the slot 11 in the side of the invention, as indicated at Fig. 4, showing a broken vertical section of the side of the cut-off, taken on line X X of Fig. 4.

In practice the lower end of the down-spout from the eaves-trough of a building is inserted in the stem at 1 in the upper end of the cut-off, and in time of a storm or down-pour of rain the water will pass to the revolute cylinder 2, said cylinder being provided with an opening or a cut-away in the side thereof, as indicated at 3. The water will make its exit through said cut-away 3 and

pass out through stem 4 into the cistern or sewer-pipe, of which one of each is connected to said stems 4 at 5 and 6.

To insure perfect movement of the revolute cylinder, I have provided a stud or wrist-pin 7, which is rigidly secured to the bottom of the cut-off and upon which the revolute cylinder is loosely journaled, as indicated at Fig. 1. It will further be observed that the upper end 8 of the revolute cylinder 2 loosely encircles the lower end of stem 1 of the cut-off, which is especially made in practice so that said cylinder will revolve freely. When the revolute cylinder is to be shifted from one exit to the other, handle 9 is grasped between the thumb and fingers and raised upward, as indicated by dotted lines in Fig. 6, until stem 10 is brought upward fair to slot 11. When in this position, with a slight pull stem 10 is drawn out through the slot, causing the revolute cylinder to turn or revolve on pivot 7, when the cylinder in this manner is revolved about one-fourth of its diameter. With a slight push inward of handle 9 it is revolved about another fourth, when it is in the position indicated by the dotted line at Fig. 3, and the downpour of water is shifted from exit-stem 5 to exit-stem 6, and vice versa, as the case may demand. It will further be observed when the handle-stem 10 is in the position indicated at Fig. 6 it forms a lock with the side of the cut-off, which holds the revolute cylinder in a desired position until it is to be shifted or reversed from one exit to the other. The opposite end of stem 10 from the handle 9 is bent at a right angle down and inserted into ear 12, which is secured to revolute cylinder 2 over the cut-away portion.

Having now fully described my invention, what I claim as new, and desire to secure by Letters Patent of the United States, is—

A cut-off for down-spouts comprising a body portion having two parallel sides and two downwardly-diverging sides, a cylindrical collar fitted in the top of said body portion, a plate secured across the bottom of said body portion and having two outlet-openings therein, an open-topped cylindrical sleeve having its upper end loosely embracing said col-

lar and an opening in its side, a crescent-shaped cut-off plate secured to said sleeve, having its concavity below said opening, a pivot-pin passing through said cut-off plate and secured to the bottom of said body portion, said pin being concentric with said sleeve, a horizontal slot in said body portion, and a stem 10 pivotally connected to said cylinder

and projecting through said slot to form a handle for rotating said cylinder and cut-off.

In testimony whereof I affix my signature in the presence of two witnesses.

MARION C. HARRISON.
